TELEPHONE SYSTEM

Imre Molnar, Chicago, Ill., assignor to Automatic Electric Laboratories, Inc., Chicago, Ill., a corporation of Delaware

Application August 28, 1944, Serial No. 551,489

28 Claims. (Cl. 179—23)

The present invention relates in general to automatic telephone systems, and more particularly to multi-exchange systems in which the different exchanges are connected by trunk lines connected at each end to an automatic two-way impulse repeater, and in which control is exercised over a ground return circuit superimposed on the interconnecting trunk lines. These ground return control circuits are most often employed on long trunks in order to reduce the effective resistance and may be arranged for either simplex or composite operation, the former utilizing both sides of the trunk in parallel, and the latter using only one leg of the trunk, with suitable arrangements to prevent interference between control and speech circuits.

In such systems it may and often does, happen that the batteries at the various exchanges are at different potentials, or that the exchange grounds are at different potentials, and that these differences in potential between two given exchanges may be such as to cause false operation of the control equipment under certain conditions, particularly when the system is at rest, with both ends of the control trunk normal and ready to receive signals.

The main object of my invention is therefore the provision of simple and inexpensive means at the terminal ends of the control circuits to prevent the flow of current over these circuits due to the presence of unbalanced potentials as previously described, during periods when no current is supposed to flow. It is known that methods have been devised for neutralizing or offsetting the effects of such potential differences in trunk circuits, but most such systems require the use of a separate neutralizing conductor, or are quite expensive, or both, whereas the method here described operates over the regular control conductors, is low in cost, and adds no complexities to the circuits.

Another object of the invention is to provide improved repeater and trunk arrangements of the character described, wherein magneto telephone waystations may be inserted in the trunk circuit, with facilities whereby the various waystations may call one another, make calls through the repeater at either end of the trunk and into the associated automatic exchange, or receive calls from either exchange through the associated repeater.

The main feature of the invention lies in the provision of a unidirectional current conducting device such as a copper oxide rectifier, in the circuit between the line battery terminals and the

control relays directly associated with the ground return control circuits in each repeater. These control circuits, which permit two way operation, supervision and release through the repeaters at the ends of the trunk by the well known method of changing the connections from battery to ground or vice versa at each end of the control circuit as required, are thereby guarded against the effect of differences in battery or ground potentials, as previously indicated. These rectifier discs may be connected in series with either or both sides of the line battery, and separate discs would normally be provided for the control relays of each trunk, where more than one trunk is employed. The use of common groups of discs for more than one trunk is also possible however, as will be described later, and either arrangement will fall within the intended scope of the invention.

Another feature of the invention in connection with the potential guarding arrangement lies in the fact that this feature does not depend on any particular type of trunk, or on any special arrangement of the ground return control circuits, but can be applied to almost any system of this nature, by simple insertion, without other change. It is for example, equally applicable to simplex or composited trunks, whether automatic or manual. It is also applicable to duplex telegraph circuits operating over composited trunk lines. This universality derives from the fact that it operates over the regular control conductors, without effect on the normal control functions.

A further feature of the invention consists in the arrangement permitting the use of waystations in a simplex trunk circuit between two automatic exchanges with a two-way automatic repeater at each end of the trunk, and the provision in each repeater of a code switch for signalling the waystations by means of automatic code ringing, in accordance with the number dialed.

Still another feature of the invention provides for the instantaneous busying of the repeater at the other end of the trunk on such a call, and in the grounding of the trunk by the called waystation upon answering, in order to cut off the ring. Both repeaters are made busy on calls between exchanges, on calls between either exchange and a waystation, either to or from the waystation, and on calls between waystations. This last type of call does not affect the repeaters otherwise.

Other features of the invention will be appar-

ent from the following specification, having reference to the accompanying drawings, comprising Figures 1 through 10.

Figures 1, 2 and 3 of the drawings show the circuit of the automatic two-way, simplex-dialing, code ringing repeater required at each end of the trunk for extending and receiving calls, and for signalling the waystations. For convenience in following the operation, the three sheets comprising the complete circuit should be placed side by side in the order named, with the interconnecting leads properly aligned.

In Figure 1, the trunk end of the repeater, the incoming end of a simplex trunk comprising conductors 1 and 2 is shown in the upper portion of the sheet, suitably terminated in the repeating coil A. At B in the lower left portion of this sheet is the code switch which selects the ringing code to be applied to the trunk on calls to a waystation. This is a ten point stepping switch capable of following dial pulses commonly known in automatic telephone practice as a minor switch, and is provided with stepping and release magnets and off-normal springs as indicated. The bank contacts of this switch are shown connected to the code ringing equipment C, comprising a source of alternating ringing current and an automatic code interrupter, with starting control therefor vested in the repeater. When in operation, grounded ringing current from the ringing machine passes through the code interrupter which breaks it up into long and short pulses, and impresses it on the banks of the code selector switch in the form of a standard ringing code, a different code being applied to each bank contact. This permits impressing different ringing codes on the trunk on waystation calls by positioning the code selector switch on the proper bank contact, which occurs automatically when the waystation number is dialed.

Figure 3 shows the exchange end of the repeater. As indicated conductors 3, 4, 5, 6, 7 and 8 are connected to the banks of one or more selectors such as E to permit the seizure of the repeater for outgoing calls, while conductors 9, 10 and 11 are connected to the operating end of an incoming selector D. These selectors may be considered as being two motion automatic switches of the well known Strowger type, having a vertical motion controlled by dial pulses, and an automatic rotary or trunk hunting motion of the wipers into the selected level of bank contacts, represented by horizontal lines beneath the selector, each line representing 10 contacts. In practice the holding or busying conductors 5, 8 and 11 would be connected to a separate bank of the same switch, but in the drawings both banks have been combined into a single bank, for simplicity. It should be noted that conductors 3, 4 and 5 are connected to a different bank level in selector E than conductors 6, 7 and 8 in order to provide two points of access to the repeater on outgoing calls, one for through calls to the distant exchange, and one for calls to a waystation. The code selector switch is automatically cut into the circuit in the second case but not in the first case, while dialing on the trunk occurs only in the first case.

In Figure 4 is shown a diagrammatic representation of the trunk layout, the square G representing the repeater at one end of the trunk, R, S and T the waystations, and conductors 1 and 2 the trunk conductors. The open conductors 1

and 2 at the edge of the sheet may be considered as leading to the trunk conductors 1 and 2 of Figure 1. If therefore Figure 4 is placed to the left of Figures 1, 2 and 3 with conductors 1 and 2 aligned the complete circuits will be shown by the four figures, Figures 1, 2 and 3 being the repeater at the other end of the trunk identical with repeater G.

In square T of Figure 4 is shown a typical circuit of one of the magneto telephone waystations, and the method of connecting it into the trunk line. Trunk splitting keys for opening the trunk in one direction when dialing in the other direction from the waystation are indicated at 200 and 201. A hand generator is shown at 202, a ringer at 203, and dial impulsing and shunt springs at 204 and 205. The hook switch is provided with two sets of springs 206 and 207, and has two operated positions. When the receiver is removed the hook switch operates only part way, closing contacts 206 and connecting the receiver 208 and the transmitter 209 to the trunk. Complete operation is by a hook latch indicated at 213. Upon the tripping of this hook latch by the subscriber, the hook switch operates fully and closes contacts 207, which connect ground to the center point of the ringer and thence to both sides of the trunk in parallel. The hook latch is automatically reset upon restoration of the receiver, as are the trunk splitting keys.

Figure 5 shows the basic arrangement of the potential guarding scheme as applied to the simplex trunk of Figure 1. The rectifiers which guard against differences in battery potential while the system is at rest with both ends of the control circuit connected to negative battery, are shown solid at 241 and 241'. Additional rectifiers are also shown dotted in the ground side of the battery at 251 and 251' for guarding against the effect of differences of ground potential when both ends of the control circuit are connected to this side of the battery. As previously indicated, either or both sets of rectifiers may be employed, as conditions warrant.

In this figure, the trunk conductors, which are common to both speech and control circuits are shown at 201 and 202. The control circuits are connected to the trunk through coils 220 and 220', which are not affected by voice currents and by their impedance exclude these from the control circuits. The condensers in the trunk side of the repeating coils A and A' on the other hand, prevent the passage of control currents from one leg of the trunk to the other, but permit passage of voice currents.

The control circuit is shown in the normal position, with both ends connected to the negative terminals of their respective line batteries through relays 228 and 228'. Under this condition no current should flow, and the relays should remain at normal. If the battery potentials are not the same at any given time however, current will tend to flow over this circuit. This will be prevented with the arrangement shown, by one of the rectifiers 241 or 241' depending on the direction of the current flow, it being understood that current will flow through the rectifiers in the direction of the arrow head, but not in the opposite direction.

Similarly, if relays 235 and 235', which are controlled from other circuits in the repeater not shown, are operated at the same time, as they are during conversation, both ends of the control circuit are connected to the ground terminals of their respective line batteries, through

relays 229 and 229'. Under this condition again, no current should flow and the relays should not operate, or if previously operated should release. Differences in ground potential however would tend to cause current to flow and perhaps interfere with the proper operation and release of these relays. Insertion of rectifier discs as at 251 and 251' in this circuit would prevent this in the same manner as explained for discs 241 and 241'. With relay 235 operated and 235' normal, ground is connected to the left end of the control circuit and battery to the right end of the circuit. The rectifiers are without effect since the arrow heads are now in the correct direction, and full battery current flows, operating relays 229 and 229'. Similarly, if relay 235' is operated and 235 normal, ground through relay 229' is connected to the right end of the circuit and battery through relay 228 to the left end of the circuit, causing full battery current to flow in the opposite direction to operate relays 229' and 228, again without interference from the rectifiers.

Figure 6 shows the same potential guarding arrangement applied to the Morse or control leg of a composited trunk. As is well known, this type of trunk provides a separate control circuit over each side of the trunk such as conductor 302, by means of condensers and retard coils such as indicated at 303, 304, 303' and 304' which serve to keep the control currents out of the voice circuits, and voice currents out of the control circuits. The numerals 338 and 338' indicate a standard form of differential relay connected to each end of the control conductor 302 over one winding and to an artificial balancing line and biasing circuit such as shown at 305 and 306, over the other winding, said artificial line having the same characteristics as the trunk line.

The common side of both windings of the differential relays is normally connected to ground, and is arranged for being switched from ground to battery and vice versa as required for the operation of the system, by relays 335 and 335', under control of other circuits not shown. Rectifier discs in both sides of the battery are indicated at 307, 308, 307' and 308'. Protective lamps are shown at 309 and 309', and thump killing reactors at 310 and 310'.

With the system at normal as shown, and ground on both ends of the control circuit, a local current will flow from ground to battery through the lower winding of the differential relay and the artificial line. This biases the differential relays to their released position. No current should flow over the control circuit comprising the upper winding of the relay and the trunk conductor 302. In the case of differing ground potentials, current will tend to flow in this circuit but will be prevented by the rectifiers 308 or 308', in the manner previously described.

If pole changer relay 335 is now operated, it will connect negative battery to that end of the control circuit, and full battery current will flow over conductor 302 to operate the distant differential relay 338'. The local differential relay will not operate at this time due to opposing polarities in its windings. If now pole changer relay 335' is operated, it will connect negative battery to the other end of the trunk, stopping the current flow over conductor 302. This will cause the operation of differential relay 338 without releasing relay 338' since neither relay is now biased to the release position. In the case of differing battery potentials, current will tend to flow over conductor 302 at this time, but will

be prevented by the rectifiers in the battery side of the circuit. The operation is similar in either direction.

Figures 7 and 8 show two methods of connecting the rectifier discs into simplex control circuits when two or more simplex trunks such as shown in Figure 5 are involved. It will be noted that these two figures are the same as the left end of the control circuit of Figure 5 except for having added connections to a second trunk. The same reference numerals are employed for this reason, 228 and 229 being the control relays associated with the first trunk, and 228' and 229' being the control relays associated with a second like trunk at the same exchange. Figures 7 and 8 are similar to each other except that in Figure 7 separate rectifier discs are shown in the circuit of each relay, while in Figure 8 a common disc or group of discs is employed in each side of the battery and multiplied to the various relays as indicated.

Figures 9 and 10 similarly show the same two methods of connecting the discs into two or more control circuits associated with composited trunks such as shown in Figure 6. These figures are the same as the left portion of the control circuit of Figure 6 except for the multiple trunk connections and the omission of the artificial line, and use the same numeral designations 338 being 30 the differential relay in the first control leg, and 338' a similar relay associated with a second control leg in the same exchange. Figure 9 shows individual discs and Figure 10 shows common discs.

35 A detailed description of the operation of the repeater and waystation circuits as shown in Figures 1, 2, 3 and 4 will now be given, in order to provide a complete disclosure of the invention. It should be understood however, that the arrangement shown is representative only, and that minor modifications could be made therein without departing from the spirit of the invention.

Repeater to repeater call outgoing

45 Under this heading the action of the repeater at the originating exchange on a through call to the distant exchange will be considered. On such a call, the first part of the number dialed by the calling party will cause an outgoing selector such as shown at E in Figure 3 to raise its wipers to the "through switching" level here indicated as level "0," and to hunt and seize an idle repeater such as that shown, the line wipers being thereby connected to the talking conductors 3 and 4, and the busying or holding wiper to busying conductor 5 of the repeater.

Ground from the busying wiper is now passed forward to conductors 5 and 42 and thence through the upper winding of the pole changing relay 35 to battery. This winding alone however, does not have sufficient power to operate relay 35 which therefore remains normal. A branch of this same circuit also extends over conductor 43 through the normally closed contacts 44 of relay 30, the normally closed contacts 45 of relay 32, and the winding of switching relay 33 to negative battery.

Switching relay 33 operates over this circuit and locks direct to the ground on the busying conductor 5 by way of its make contacts 46. Relay 33 at its contacts 47 disconnects the incoming selector D from the circuit by opening conductor 10, and at its contacts 49 and 53 connects the outward pulsing relay 27 to the local calling loop over

the following circuit: ground through the lower winding of relay 27, the normally closed contacts 48 of relay 31, make contacts 49 of the operated relay 33, conductor 50, winding 100 of the repeating coil A, conductor 51, loop conductor 4 to the bank of selector E, through the calling loop and back over loop conductor 3, winding 101 of the repeating coil, conductor 52, make contacts 53 of relay 33, normally closed contacts 54 of relay 31, and the upper winding of relay 27 to negative battery. Relay 27 operates over this circuit to busy the repeater and prepare it for dialing.

Switching relay 33 at its back contacts 55 also disconnects negative line battery from the trunk preparatory to the grounding of the trunk to seize the distant repeater. As previously stated, the repeater maintains negative battery on the trunk when at normal. This circuit is as follows: line battery from Figure 1, rectifier disc 41, conductor 56, upper winding of control relay 28, conductor 95, break contacts 57 of relay 38, break contacts 58 of relay 35, conductor 96, break contacts 55 of relay 33, conductor 59, break contacts 60 of relay 22, both windings of the simplex relay 20, windings 102 and 103 of the repeating coil, back contacts 61 and 62 of relay 23, back contacts 63 and 64 of relay 21, and trunk conductors 1 and 2 in parallel. With a similar arrangement at the distant end of the trunk negative battery encounters negative battery and no current flows, the rectifier discs, as previously explained acting to prevent current flow should the battery potentials vary at times.

Operation of the outward pulsing relay 27 causes the operation of release relay 32 from ground at make contacts 65, and also connects line ground to the trunk through control relay 29 over the following circuit: line ground from Figure 1, conductor 66, control relay 29, make contacts 67 of the operated relay 21, make contacts 55 of the operated relay 33, conductor 59 left, back contacts 60 of relay 22, both windings of simplex relay 20 in parallel and out over both sides of the trunk by way of the repeating coil and back contacts of relays 21 and 23 to negative battery at the distant repeater, through the distant control relay 28, which operates to seize the distant repeater and prepare it for receiving dial pulses. Control relay 29 in the calling repeater also operates over this circuit.

Meanwhile, the operation of release relay 32 has busied the calling repeater to the local switch train by grounding conductor 5 to the outgoing selector E by way of make contacts 45 of relay 32, back contacts 44 of relay 30 and conductor 43. At its make contacts 68 relay 32 also closes a circuit over conductor 99 to relay 40, which operates to disconnect relay 39 so that the latter relay will not operate should anyone ring on the trunk at this time, through inadvertance or otherwise.

The operation of control relay 29 completes a circuit to relay 37 as follows: ground on the busying conductors 5 and 43, conductor 69, conductor 70, make contacts 71 of relay 29, conductor 72, break contacts 73 of relay 38, and the winding of relay 37 to negative battery. Relay 37, whose functions are merely incidental or preparatory at this time, operates over this circuit and locks to the busying lead by way of make contacts 74 and conductor 70. Relays 27, 29, 32, 33, 37 and 40 are now operated, and the repeater is ready for dialing.

The distant switch train now returns dial tone over trunk conductors 1 and 2, said dial tone passing through the repeating coil by in-

duction and thence to the calling party by way of line conductors 3, 51 and 4, passing freely like voice currents through condensers 173 and 174 of the repeating coil. The calling party then 5 proceeds to dial the number of the wanted party in the distant exchange, thereby pulsing relay 27 over the calling line loop. At each restoration of relay 27, its make contacts 65 open the circuit to release relay 32 momentarily, but relay 10 32 being slow to release due to having a copper sleeving over its magnetic iron core, remains operated. On the first restoration of relay 27 relay 25 operates over the following circuit: ground through back contacts 65 of relay 27, 15 back contacts 75 of control relay 28, make contacts 76 of release relay 32, break contacts 77 of relay 31 and the winding of relay 25 to negative battery. This circuit is of course interrupted at each re-operation of pulsing relay 27 20 but relay 25 being made slow to release, remains operated during each digit, restoring only between digits and after the last digit. When operated, relay 25 at its make contacts 78 shunts winding 100 of the repeating coil to improve the 25 loop dialing, and at its make contacts 79 shunts control relay 29 with the non-inductive resistor 80 in order to improve the pulsing on the trunk. This shunt may be traced as follows: left side of the winding of relay 29, resistor 80, make contacts 30 79 of relay 25, conductor 81, back contacts 82 of relay 36, conductor 83 and the right side of the winding of relay 29.

The pulsing circuit to the trunk from line ground is now therefore through control relay 35 39 and resistor 80 in parallel and thence through the interrupting contacts 67 of pulsing relay 27 and to the trunk by way of make contacts 55 of relay 33 and conductor 59. The circuit of control relay 29 is opened momentarily at each 40 release of pulsing relay 27 but being made slow to release by the action of the shunt, relay 29 remains operated. The control relay similar to relay 28, in the distant repeater, follows the pulses however and repeats them to the distant 45 switch train, which establishes connection to the called party's line. The distant exchange then rings the called station automatically or returns busy tone as required. On a call to a busy station the busy tone like dial tone, comes back 50 over trunk conductors 1 and 2, through the repeating coil to loop conductors 3 and 4 and thence to the calling party.

When the called station answers, the distant repeater places ground on the trunk in place 55 of battery, restoring control relay 29 which now has ground on both sides of it. Control relay 29 on releasing completes a circuit at its break contacts 86 to the battery reversing relay 31. This circuit is as follows: holding ground from 60 conductors 5 and 43, make contacts 46 of relay 33, conductor 84, break contacts 85 of relay 25, break contacts 86 of relay 29, conductor 87, break contacts 88 of relay 36, conductor 89, back contacts 90 of relay 22, conductor 91, make contacts 92 of relay 37, conductor 93, and the winding of relay 31 to negative battery. Relay 31 operates and at its contacts 48 and 54 reverses the battery from relay 27 to the calling loop for supervisory or other purposes as required. The connection is now complete with the talking circuit extending through the repeating coil and relay 27 furnishing talking battery to the calling line. Relays 27, 31, 32, 33, 37 and 40 are operated and ground is on both ends of the trunk. At the termination of the call, if the calling

party disconnects first, holding ground through the selector E is removed from conductor 5, and the calling loop to pulsing relay 27 is opened. Relay 27 thereupon restores, disconnecting line ground from the trunk at its make contacts 67. Contacts 65 also open the circuit to release relay 32 which restores. Relay 32 releasing, opens the circuit through its contacts 68 to relay 40 which thereupon restores. The release of relay 32 also opens make contacts 45 thereby removing busying ground from conductor 43, and releasing relays 31, 33 and 37 which were held operated by this ground after the removal of holding ground from conductor 5. Relay 33 at its back contacts 55 re-connects line battery through the upper winding of control relay 28 to the trunk to signal the distant repeater. Control relay 28 operates over this circuit and re-operates relays 32 and 40 to hold the repeater busy until the called party disconnects. The circuit to relay 32 is now from ground at back contacts 65 of pulsing relay 27, make contacts 75 of control relay 28, back contacts 94 of relay 30 to relay 32 and negative battery. Relay 40 opens the circuit to relay 39 as before and relay 32 again connects busying ground to conductor 43.

When the distant called party now disconnects the distant repeater returns negative battery over the trunk and since negative battery is now again on both ends of the trunk, control relay 28 restores, releasing relays 32 and 40. The repeater is now normal and ready for another call, in either direction.

If the distant called party disconnects first, the distant repeater places negative battery on the trunk. It will be remembered that during conversation relays 27, 31, 32, 33, 37 and 40 were operated and ground was on both ends of the trunk through control relay 29. Negative battery from the distant end of the trunk therefore causes the operation of control relay 29. Control relay 29, upon operating, opens at its break contacts 86, the circuit from holding ground through make contacts 46 of relay 33, conductor 84 and break contacts 85 of relay 25 to the battery reversing relay 31. Thereupon relay 31 releases and at its contacts 48 and 54 reverses the battery feed from relay 27 to the calling loop, for release supervision.

When the local calling party then disconnects, holding ground through selector E is removed from conductor 5, and the calling loop to relay 27 is opened as before. Relay 27 now restores, and at its contacts 67 disconnects control relay 29 and its associated line ground from the trunk, and relay 29 releases. Contacts 65 of relay 27 open the circuit to release relay 32 which also releases, and at its contacts 45 removes busying ground from conductor 43. This unlocks relays 33 and 37 which now restore. Relay 40 also releases upon the release of 32, due to the opening of contacts 68. The release of relay 33 re-connects negative battery to the trunk through control relay 28 by way of back contacts 57, 58 and 55 and conductor 59 as before. Negative battery is now on both ends of the trunk, and the repeater is again normal and ready for another call.

Repeater to repeater calls incoming

On an incoming call from the distant exchange, ground on the trunk from the distant repeater causes the operation of control relay 28 over the previously described circuit which will be re-traced for clearness as follows: ground from trunk

conductors 1 and 2, back contacts 63 and 64 of relay 21, back contacts 61 and 62 of relay 23, windings 102 and 103 of the repeating coil, both windings of the simplex relay 20 in opposition, back contacts 60 of relay 22, conductor 59, back contacts 55 of relay 33, conductor 96, back contacts 58 of relay 35, break contacts 57 of relay 38, conductor 95, upper winding of control relay 28, conductor 56, rectifier disc 41 to negative line battery.

Control relay 28 operating, closes a circuit to release relay 32 as follows: back contacts 65 of the outward pulsing relay 27, make contacts 75 of relay 28, back contacts 94 of relay 30, and the winding of relay 32 to negative battery. Relay 32 operates, busies the repeater as before by grounding conductors 43 and 5 through its make contacts 45 and back contacts 44 of relay 30, and at its make contacts 68 closes a circuit to relay 40 which also operates to cut off relay 39 and prevent the latter from acting in case a waystation should inadvertently ring on the trunk at this time. The grounding of conductor 43 also energizes the upper winding of relay 35, but this relay will not operate over its upper winding alone. Nor does switching relay 33 operate, since its circuit is opened at contacts 45 of relay 32 at the same time that ground is placed on conductor 43 by these contacts.

The operation of control relay 28, at contacts 105 also closes the loop circuit of the incoming selector D to seize this selector. This circuit may be traced as follows: positive line conductor 10, break contacts 47 of relay 33, conductor 51 left, winding 100 of the repeating coil, conductor 50, lower winding of relay 35, resistor 97, conductor 98, back contacts 53 of relay 33, conductor 52, winding 101 of the repeating coil, conductor 3, make contacts 105 of control relay 28, break contacts 106 of relay 30 and back to the selector over the negative line conductor 9. The incoming selector is seized thereby and made ready to receive dial pulses, returning dial tone to the distant exchange. This dial tone circuit is as follows: line conductor 10, break contacts 47 of relay 33, conductor 51, winding 100, condenser 174 and winding 101 of the repeating coil, conductor 3, make contacts 105 of relay 28, break contacts 106 of relay 30, and line conductor 9 back to the selector. At the repeating coil it is induced into trunk conductors 1 and 2 and thence to the distant repeater and to the calling party. Both windings of the pole changer relay 35 are now energized, but in opposition, so that this relay still remains normal. Only relays 28, 32 and 40 are operated at this time.

When dialing begins at the distant exchange the control-and-inward-pulsing relay 28 follows the ground pulses on the trunk, and repeats them through its contacts 105 to the incoming selector and the local switch train which respond and make connection to and ring, the called station. Relay 25 operates on the first pulse of each digit as before from ground through back contacts 65 of the unoperated relay 21, and closes contacts 78 to improve the loop pulsing. The interruptions in the circuit of relay 25 are now from the break contacts 75 of relay 28, but this relay as before, releases only between digits and shortly after the last digit.

When the local called line answers, the local switch train reverses battery to the previously traced loop circuit, which reverses the current in the lower winding of relay 35 which is a part

of this circuit. The polarities of the two windings of this relay are now aiding each other, and relay 35 operates to ground the trunk as a supervisory signal to the distant repeater. Relay 29 in the distant repeater thereupon restores and causes reversal of battery to the calling loop in the distant exchange in the manner explained for an outgoing call, through the operation of the distant relay 31. This provides answer supervision, in cases where an operator is involved in the call.

Relay 35, at its contacts 107, connects ground to the lower winding of control relay 28 by way of conductor 108 and break contacts 109 of relay 29, to prevent relay 28 from releasing when its upper or series winding is opened. Relay 35 also, at its contacts 58, disconnects negative line battery through control relay 28 from the trunk and connects line ground through control relay 29 in its stead as stated. Control relay 29 does not operate at this time however, since ground is now again on both ends of the trunk. The connection is now complete, with talking battery furnished to the called party from the local switch train. Repeater relays 28, 32, 35 and 40 are operated, and ground is on both ends of the trunk.

If the called station is found busy, of course the local switch train will not ring, but will return busy tone to the calling party instead. This busy tone reaches the repeating coil in the same manner as dial tone, by way of line conductors 9 and 10 from the incoming selector, contacts 47, 106 and 105 and conductors 3 and 51, and is similarly passed through the repeating coil by induction to the trunk conductors 1 and 2, and thence through the distant repeating coil to the calling line. The calling party on hearing the busy tone will disconnect and attempt the call later.

At the termination of the call, if the calling party disconnects first, the distant repeater, as previously explained for an outgoing call, partly releases, restoring its switching relay 33, which at its contacts 55 re-connects negative line battery through relay 28 to the trunk in place of line ground.

Control relay 29 at the called repeater now operates from the negative line battery on the trunk, and at its contacts 71 completes a circuit to relay 31 as follows: ground from conductor 43, conductor 69, conductor 70, make contacts 71 of relay 29, conductor 72, break contacts 73 of relay 38, and the winding of relay 31 to negative battery. Relay 31 operates and locks, and at its contacts 113 opens the incomplete circuit to relay 38 to prevent the premature operation of this relay. Control relay 29 also, at its break contacts 109 opens the holding circuit to the lower winding of control relay 28, which then releases. Control relay 28, at its contacts 105, opens the called line loop to release the local switch train, and at its contacts 75 opens the circuit to release relay 32 which restores. Relay 32 at its contacts 68 opens the circuit of relay 40 and at its contacts 45 opens the circuit to the upper winding of relay 35, and both of these relays also restore. Relay 35 at its contacts 58 disconnects control relay 29 and line ground from the trunk and re-connects line battery through control relay 28 in its stead. Relay 29 releases and the repeater is once again normal with negative battery on both ends of the trunk.

If the local switch train is arranged for last party release however, it will not release, but will maintain ground on conductor 11, and upon the release of relay 32 as explained in the pre-

ceding paragraph will cause the operation of relay 38 by way of break contacts 110 of relay 25, break contacts 111 of relay 32, conductor 112, break contacts 113 of relay 37, and winding of relay 38 to negative battery. Relay 38, at its break contacts 57 disconnects control relay 28 from the trunk, and at its make contacts 114 connects line ground through control relay 29 to the trunk to seize and hold the distant repeater. The circuit is thus held busy to further calls until the called station has also disconnected. When this occurs, ground is removed from conductor 11, and relay 38 restores. Relay 38 at its contacts 114 disconnects line ground through control relay 29 from the trunk and at its contacts 57 re-connects line battery through control relay 28. Relay 29 releases and the repeater is again normal with negative battery on both ends of the trunk.

If the local called party disconnects first, it being remembered that relays 28, 32, 35 and 40 were operated during conversation, and that line ground through control relay 29 was connected to both ends of the trunk, the local switch train reverses battery over the called line loop through the lower winding of relay 35. Since the polarities of the two windings of relay 35 are now opposed to each other this relay restores. Relay 35 at its pole changing contacts 58 disconnects control relay 29 and line ground from the trunk, and connects line battery through control relay 28 to the trunk in its stead, to give release supervision to the distant exchange. Relay 35 also at its contacts 107 opens the circuit to the lower winding of control relay 28 which is however now held operated over the trunk. Relays 28, 32 and 40 are therefore still operated.

When now the distant calling party disconnects, the distant repeater puts negative battery on the trunk causing the release of control relay 28 which at its contacts 75 causes the release of relay 32 and at its contacts 105 opens the called line loop through relay 35, releasing the local switch train. Relay 32 at its contacts 45 opens the circuit to the upper winding of relay 35 which is already released however, and at its contacts 68 relay 32 opens the circuit of relay 40 which restores. The repeater is again normal and ready for a new call.

50 Repeater to waystation calls.

Under this heading, the action of both repeaters on an automatic call to a waystation will be considered, with the operation of the repeater at the originating exchange being considered first, and the manner of the busying of the distant repeater last. On such a call, the first part of the number dialed by the local calling party will cause an outgoing selector such as E to raise its wipers to the "code ringing" level here shown as level "8," and to hunt and seize an idle repeater such as shown. The line wipers of the selector will be thereby connected to the talking conductors 6 and 7 of the repeater, and the busying wiper to the busying conductor 8. It will be noted that the negative line conductor 6 from this level passes through the upper winding of a pole changer relay 36 and thence to the repeating coil.

The outgoing selector, on connecting through to the repeater, passes ground forward over the busying wiper to conductors 6 and 43, causing the operation of switching relay 33 as for a through call, by way of break contacts 44 and 45 of relays 30 and 32. This same ground also energizes the

upper winding of relay 35, but this is without effect and relay 35 remains normal.

Switching relay 33 operating, locks direct to conductor 43 at contacts 46, at contacts 55 disconnects control relay 28 and negative battery from the trunk, at contacts 47 disconnects the incoming selector, from the repeater, and at contacts 49 and 53 connects pulsing relay 27 to the local calling loop over the following circuit: ground through the lower winding of relay 27, back contacts 48 of relay 31, make contacts 49 of relay 33, conductor 50 left, winding 100 of the repeating coil, conductor 51, the loop conductor 7, through the selector bank and the calling loop and back to the selector bank and loop conductor 6, the upper winding of pole changer relay 36, conductor 3 left, winding 101 of the repeating coil, conductor 52, make contacts 53 of relay 33, back contacts 54 of relay 31, and through the upper winding of relay 27 to negative battery. Relays 36 and 27 operate in series over this circuit.

Pole changer relay 36 upon operating completes a circuit to its own lower winding as follows: ground from busying conductor 8, conductor 42, break contacts 115 of relay 26, conductor 116, make contacts 117 of relay 36, and the lower winding of relay 36 to negative battery. Both windings of relay 36 are now aiding and this relay remains operated. Relay 36 at its make contacts 118 also prepares the "pick up" circuit which is associated with the ringing equipment, and at make contacts 82 connects line ground through control relay 29 to the trunk to seize and busy the distant repeater. This circuit is from line ground and conductor 66, through relay 29, conductor 83, make contacts 82 of relay 36, conductor 123, make contacts 55 of relay 33, conductor 59, back contacts 60 of relay 22, and thence to relay 20 and out over the simplex. Contacts 82 of relay 36 also shunt the pulsing contacts of relay 27 in order to prevent pulsing on the trunk. This shunt may be traced as follows: upper contact 67, conductor 83, make contacts 82 of relay 36, conductor 123, and back to lower contact 67. Relay 29 operates, and at its contacts 71 completes a circuit to relay 37 which operates and locks to conductor 43. Finally, at its contacts 124, relay 36 prepares a pulsing circuit to the motor magnet 126 of the code selector switch B.

Pulsing relay 27 upon operating establishes, at its make contacts 67, a second circuit for line ground to the trunk through make contacts 55 of relay 33, at its make contacts 65 closes a direct circuit to release relay 32 which operates and at contacts 76 further prepares the pulsing circuit to the code selector switch. Relay 32 also operates relay 40 as before to disconnect relay 39 and prevent operation of the latter relay should a waystation happen to ring on the trunk at this time, and at its contacts 45 connects repeater busying ground to conductor 43 as before, so that conductor 43 is now grounded both from the repeater and from the outgoing selector.

Relay 37 upon operating, at its make contacts 127 shunts the series winding of relay 36 in order to improve the pulsing on the local loop, at its make contacts 92 prepares the circuit to battery reversing relay 31, and at make contacts 128 prepares a locking circuit to the pick up relay 34. Relays 27, 29, 32, 33, 36, 37, and 40 are now operated, and the repeater is ready for dialing.

When the calling party dials the final digit of the waystation number, relay 27 will follow the

dial pulses. The outward pulsing contacts 67 of relay 27 are without effect however, due to being shunted by make contacts 82 of relay 36, and there is no pulsing on the trunk. Pulsing to the code selector switch does occur however, over the following circuit: ground through back contacts 65 of relay 27, back contacts 75 of relay 28, make contacts 76 of relay 32, conductor 163, make contacts 124 of relay 36, conductor 125 and the winding of motor magnet 126 to negative battery. This causes the code selector switch to step one step at each release of relay 27 and position its wipers in accordance with the digit dialed. Relay 25 operates on the first pulse in parallel with the foregoing circuit, through break contacts 11 of relay 31, and at contacts 78 shunts winding 100 of the repeater to improve the pulsing on the loop. Break contacts 85 of this relay open a circuit to the off normal springs 130 of the code selector switch preparatory to the closing of these springs which occurs as the switch wipers move away from their normal position on the first step. Relay 25 remains operated during the pulsing.

Relay 25 on releasing shortly after the last pulse of the digit, causes the operation of ring start relay 24 over the following circuit: ground from conductor 43, through make contacts 46 of relay 33, conductor 84, break contacts 85 of relay 25, conductor 129, code selector off normal springs 130, and the winding of relay 24 to negative battery. Relay 24 upon operating locks to the ground on conductor 84 at make contacts 132 independently of the aforementioned break contacts 85 of relay 25, and at its make contacts 133 connects ground to the ringing machine start conductor 134 to start the ringing machine, and the automatic code interrupter C. Relay 24 also, at its make contacts 121 connects the ring pick up relay 34 to the pick up lead 175 which is grounded momentarily by the code ringing equipment at the end of each coding cycle to insure that ringing will not start in the middle of a code, and at contacts 139 prepares a release circuit to the code selector switch.

The code ringing equipment now starts and connects the alternating current pulses of the various ringing codes to the contacts of the code selector switch, as previously covered in the description of the drawings. When now, the code ringing equipment grounds the pick up lead 175, relay 34 operates over the following circuit: ground on conductor 175, through make contacts 118 of relay 36, back contacts 119 of relay 34, conductor 120, make contacts 121 of relay 24, conductor 122, and the winding of relay 34 to negative battery. Relay 34 at its make before break contacts 119 disconnects the pick up lead, and locks to ground at make contacts 128 of relay 37 by way of conductor 135, back contacts 136 of relay 26, and conductor 137. Relay 34 at its contacts 151 also prepares a circuit over conductor 152 to the alternating current relay 21 of Figure 1.

The grounded alternating current pulses of the ringing code of the called waystation, now pass from the selected bank contact of the code selector switch to the switch wiper and conductor 148, through the condenser 149, conductor 150, make contacts 151 of relay 34, conductor 152, and the winding of relay 21 to ground. Relay 21 follows the coded pulses and at its make contacts 63 and 64 repeats them to the trunk to signal the waystations with insulated ringing

generator via conductors 168 and 169, and thence direct to the trunk conductors 1 and 2.

Each operation of ringing relay 21 also causes the operation of drain relay 23 from ground at make contacts 165. Each operation of relay 23 in turn disconnects the repeating coil from the trunk circuit at back contacts 61 and 62, and at make contacts 61 and 62 connects resistor 170 to this circuit. Since this relay is made slightly slow to release by a copper sleeve on the core, it remains operated momentarily after each release of relay 21 in order to permit the trunk line to drain through resistor 170 after each pulse of ringing current. Condenser 171 and resistor 172, bridging back contacts 63 and 64 of relays 21 and 23, provide a path for ring back tone to line ground through winding 102 of the repeating coil during code ringing, which is then passed by induction through the repeating coil to the calling loop.

On the first operation of ringing relay 21, make contacts 166 of this relay complete a circuit to relay 22 as follows: ground on the busying conductor 43, conductor 69, conductor 70, make contacts 166 of relay 21, back contacts of the make before break springs 167 of relay 22, and the winding of relay 22 to negative battery. Relay 22 operates over this circuit and locks direct to conductor 70 and busying ground through make before break springs 167 which at the same time disconnect the pull up circuit through contacts 166. Relay 22 at its back contacts 60 disconnects control relay 29 and line ground from the trunk circuit, and at make contacts 60 connects line battery to this circuit through auxiliary control relay 26, by way of conductor 153. When therefore relays 21 and 23 restore after each code pulse, relay 26 and line battery are connected through to the trunk. Since however the distant repeater also has battery on the trunk, relay 26 does nothing at this time.

With reference to the trunk and waystation diagram of Figure 4, it will be obvious that the ringing pulses on the trunk will ring all of the waystation bells in multiple. The waystation party whose code is being rung, answers by removing his receiver and tripping the hook latch to permit full operation of the hook switch. This closes contacts 206 and 207, grounding both sides of the trunk, and also connecting the waystation talking circuits across the trunk.

Returning now to the repeater at the calling exchange, the ground on the trunk from the answering waystation causes the operation of the auxiliary control relay 26, on the next succeeding de-energization of relays 21 and 23, over the following circuit: ground from trunk conductors 1 and 2, back contacts 63 and 64 of relay 21, back contacts 61 and 62 of relay 23, windings 102 and 103 of the repeating coil, both windings of relay 20, make contacts 60 of the locked up relay 22, conductor 153, winding of relay 26, conductor 56, and through the rectifier disc 41 to negative line battery.

Auxiliary control relay 26, upon operating, at its break contacts 115 opens the locking circuit to relay 36, and at its back contacts 136 opens the locking circuit to relay 34, causing the release of both of these relays. Relay 26 at its make contacts 136 closes a circuit to battery reversing relay 31 as follows: ground through make contacts 128 of the locked up relay 37, conductor 135, make contacts 136 of relay 26, conductor 158, make contacts 90 of the locked up relay 22, conductor 91, make contacts 92 of relay 37, and con-

ductor 93 to the winding of relay 31 and negative battery.

Battery reversing relay 31 operates over this circuit and at its make before break contacts 48 and 54 reverses battery to the calling loop as before to give answer supervision. Relay 31 at its make contacts 141 also completes the release circuit of the code selecting switch as follows: ground at make contacts 138 of the locked up relay 22, make contacts 139 of the operated ring start relay 24, conductor 140, make contacts 141 of relay 31, conductor 142, code switch off normal springs 143 and the winding of the release magnet 144 to negative battery. The release magnet operates to disengage the ratchet, and the switch restores to normal by spring tension. The off normal springs then open, disconnecting the release magnet and relay 24, which both restore. Relay 24 releasing, stops the code ringing equipment by opening contacts 133 and further opens the code switch release circuit at contacts 139. The connection is now complete and the repeater is ready for conversation, with relays 22, 26, 27, 31, 32, 33, 37 and 40 operated.

Upon termination of the conversation, if the local calling party disconnects first, the calling loop is opened to pulsing relay 27 and this relay restores and releases relay 32. Relay 32 in turn releases 40 and removes busying ground from conductor 43. Since holding ground has also been removed from this lead by the switch train, relays 22, 33 and 37 which were locked to this conductor, also restore. Relay 31 also restores, due to the opening of its circuit at contacts 92 of relay 37. Relay 22 upon releasing, disconnects line battery through relay 26 from the trunk at contacts 60, causing the release of relay 26, and reconnects line battery through relay 28 to the trunk in its stead. Relay 28 now operates from waystation ground and causes relays 32 and 40 to re-operate to hold the repeater busy until the waystation disconnects.

When the waystation disconnects in turn, it removes ground from the trunk. Control relay 28 now encounters battery on the trunk from the distant repeater and is shunted down. Control relay 28 releasing, causes the release of relays 32 and 40, and restores the repeater to its normal condition.

If the waystation disconnects first, the removal of ground from the trunk at the waystation permits negative line battery from the distant repeater to shunt down relay 26 which restores. Relay 26 at its contacts 136 opens the circuit of relay 31 which was held, it will be recalled, from ground at make contacts 128 of relay 31. Relay 31 thereupon restores, and reverses the polarity of the calling loop at its contacts 48 and 54 to give disconnect supervision as previously described.

When the local calling party then disconnects, relay 27 restores on the opening of the loop circuit and releases relay 32 as before. Relay 32 causes the release of relays 22, 33, 37 and 40. Relay 22 disconnects relay 26 from the trunk and re-connects relay 28 thereto in its place. The repeater is again normal and ready for another call, and negative line battery is again on both ends of the trunk through the control relay 28 in each repeater.

The busying of the distant repeater, on a repeater to waystation call, takes place as follows. Upon the original seizure of the calling repeater, it will be remembered, its relay 36 operated to connect line ground from relay 29 to the trunk,

via make contacts 82, this circuit being from line ground through relay 29, conductor 83, make contacts 82 of relay 36, conductor 123, make contacts 55 of relay 33, conductor 59, and thence to the trunk through back contacts 60 of relay 22. Since these same contacts 82 of relay 36 also shunt the outward pulsing contacts 67 of relay 27, as previously explained, this is a solid ground, and is not affected by the dialing of the final or code selecting digit of the waystation number.

At the distant repeater, this ground causes the operation of the distant control relay 28 and the resultant operation of associated relays 32 and 40. Relay 32 grounds conductor 43 from make contacts 45 to busy the repeater, while relay 28 at contacts 105 completes the loop circuit to the incoming selector D. The distant incoming selector is seized momentarily over this circuit, and returns dial tone in the usual manner. When the calling repeater starts ringing, however, it removes line ground from the trunk causing the distant control relay 28 to release again. The distant control relay 28 at its contacts 105, opens the loop circuit to the distant incoming selector which releases, and stops the dial tone. The release of relay 28 also causes the release of relays 32 and 40 after a slight delay, due to the slow to release nature of relay 32.

Meanwhile, the ringing current placed on the trunk by the calling repeater, in addition to ringing the bells at the waystations, also causes the operation of the distant alternating current simplex relay 20, the current passing through both windings of this relay in series and thus to the other trunk conductor and back to the source. In series, the windings of relay 20 are polarized to aid each other, which permits it to respond to this current. The distant control relay 28 on the other hand is not affected, since only insulated or ungrounded ringing current is applied to the trunk, through the secondary of a ringing transformer.

The operation of relay 20 in the distant repeater closes a circuit to the distant vibrating reed relay 39 from ground at make contacts 145 of relay 20, over conductor 146, through break contacts 147 of relay 40 and the winding of relay 39 to negative battery. Relay 39 operates over this circuit and operates relay 30 from make contacts 159 over conductor 160. Relay 30 is made slow to release, for reasons which will be made clear in the next paragraph, by means of a heavy copper slug placed over the core, at the armature end of the relay. This same slug also tends to make the relay slightly slow to operate, which assures good magnetic saturation of the core before operation. The slug is indicated on the drawings at the upper end of the relay. Relay 30 upon operating, locks through its make contacts 162 and conductor 161 to ground at the springs of relay 39. Relay 30 also prepares a second locking circuit for itself at make contacts 94, and at make contacts 44 places ground on conductor 43 to maintain the busy on the repeater. Finally relay 30 at break contacts 106 opens the circuit to the incoming selector D at a second point. The distant repeater is thus held busy by its operated relay 30, but without tying up any other equipment.

In the pauses between the rings of the code, relays 20 and 39 of the distant repeater restore, but relay 39 at its springs 159, sets up an oscillating contact which holds slow relay 30 operated during these intervals. Relay 39 has a weighted vibrating reed armature, which on operation

strikes against the core of the coil and makes a firm contact from ground through itself to the associated make springs 159. Upon release however, the reed vibrates rapidly for a considerable period, and thus maintains an intermittent ground on the lower locking circuit of relay 30 over conductor 161, which prevents the release of relay 30 until the vibration of the springs has practically ceased. Relays 30 and 39 may be adjusted to vary this timing over a wide range, up to a maximum of approximately fifteen seconds.

When the waystation answers and grounds the trunk to cut off the ring at the calling repeater, control relay 28 at the distant repeater re-operates from this ground, and closes the upper locking circuit of relay 30 to ground at back contacts 65 of relay 21, through make contacts 75 of relay 28 and make contacts 94 of relay 30. Relay 30 now remains operated after relay 39 has finally come to rest following its final release, upon the cessation of ringing. Relay 32 does not re-operate from relay 28 at this time because of the open back contacts 94 on relay 30. When the connection is released, and ground is removed from the trunk, the stated distant relays 28 and 30 restore, and again free the distant repeater.

Waystation to waystation calls

Waystations on the trunk call one another by ringing the code of the wanted station with the hand generator. To make such a call, referring again to Figure 4, the calling party removes his receiver from the hook, thereby closing hook springs 206. This connects the speech elements of the telephone including receiver, transmitter and induction coil to the trunk, and the calling party now listens on the trunk to determine whether or not it is in use. If not in use, he proceeds at once to ring the code of the called station with the hand generator 202, which is arranged to automatically connect itself across the trunk at its springs 211, upon being operated, and at the same time to disconnect the ringer momentarily.

The ringing current on the trunk, in addition to ringing the bells of the other waystations, also operates the simplex relays 20 in the repeaters at each end of the trunk, passing through both windings of each relay in series. Each relay 20 causes the operation of the associated vibrating reed relay 39 over conductor 146, and each relay 39 causes the operation of its associated relay 30. The relays 30 at contacts 44 ground the 43 conductors to busy both repeaters. This prevents seizure of either repeater from the exchange end, and thus prevents interference with the waystation call. The relays 30 also at break contacts 106 open the incomplete incoming selector loop circuit, in order to prevent seizure of the selector when the called waystation answers. There is thus no dial tone on the trunk on such a call. Relays 20 and 39 release between rings, but 30 remains operated due to the vibrating action of relay 39 on release. The code signals are kept up until the called party answers.

The called waystation answers by removing the receiver and tripping the hook latch to permit complete operation of the hook switch. This closes contacts 207 of Figure 4, which connect ground to the center point of the ringer 203, through dial impulse springs 204, and so to conductors 1 and 2 of the trunk in parallel. This

ground causes the operation of the control relays 28 in both repeaters which lock up relay 30 independently of relay 39 by way of make contacts 15 of relay 28 and make contacts 94 of relay 30. The calling party now trips his hook latch also, so that ground is maintained on the trunk from both waystations.

When the conversation is completed and both waystations have disconnected, this holding ground is removed from the trunk, and relays 28 and 30 restore at both ends of the trunk and free the repeaters.

Waystation to repeater calls

Waystation calls to the automatic exchange at either end of the trunk are made by dialing from the waystation. To make such a call, the calling party first lifts the receiver and listens to make sure that the trunk is not in use. If not, he trips his hook latch to ground the trunk and busy both repeaters, through the operation of their relays 28, 32 and 40. The calling waystation then operates one of the trunk splitting keys 200 or 201 of Figure 4 depending on the direction of dialing. This disconnects the dial from the unwanted end of the trunk, but connects a direct ground to this end of the trunk to replace the dial ground, in order to maintain the busy on this repeater.

The calling waystation party now proceeds to dial the number of the wanted party in the selected exchange. On each operation of the dial, ground is pulsed to both trunk conductors in parallel in the desired direction by the dial impulse springs 204, while the dial shunt springs 205 place a shunt around the ringer coils as long as the dial is off normal, in order to improve the pulsing by removing the impedance of these coils from the circuit. The called repeater responds and completes the connection exactly as for a repeater-to-repeater or "through" call from the distant exchange. At the completion of the conversation, the waystation calling party replaces the receiver and the connection is released in the same manner as for a repeater to waystation call. The trunk splitting key and the hook latch are automatically restored to normal by the hook switch, by means of mechanical linkages commonly employed in key type telephones.

What is claimed is:

1. In a telephone system, two exchanges, a separate source of current at each of said exchanges, terminals of opposite polarity for each of said sources of current, a trunk line interconnecting said exchanges, a differential relay and associated equipment for said trunk line at each exchange, a two way ground return control circuit superimposed on said trunk line through said differential relay at each exchange, the windings of said relays being commoned on one side and said common side of said windings being normally connected to corresponding terminals of the separate sources of current at each end of said control circuit, means at each exchange for connecting the other terminal of the separate source of current to said common side of said relay in place of the normally connected terminal, means for interrupting said last named connection and for restoring the connection of said normally connected terminal to said control circuit, said control circuit and associated equipment being controlled and operated in response to said changes in the terminal connections of said control circuit, and a unidirectional current conducting device connected between each terminal

of said separate sources of current and the common side of said differential relays at each exchange to prevent faulty operation of said control circuits due to differences of potential at the two exchanges during the times that both ends of said control circuit are connected to the same respective terminals of the separate sources of current.

2. In a telephone system, two exchanges, a trunk line connecting said exchanges, a separate source of current at each of said exchanges, positive and negative terminals for each of said sources of current, a two way ground return control circuit superimposed on both conductors of said trunk line in parallel, a first relay at each exchange connected to the negative terminal of the separate sources of current, a second relay at each exchange connected to the positive terminal of the separate sources of current, said first relays being normally connected to said control circuit, means at each exchange for connecting said second relay to the control circuit in place of said first relay and for re-connecting the first relay to said control circuit thereby to operate and control said relays over said control circuit, and unidirectional current conducting devices in the circuit of said normally connected relays at each exchange to prevent current flow over the control circuit and resultant false operation of said normally connected relays due to differences of potential at the two exchanges during the times that both ends of said control circuit are connected to said negative terminals of said separate sources of current.

3. In a telephone system, two exchanges, a trunk line connecting said exchanges, a separate source of current at each of said exchanges, positive and negative terminals for each of said sources of current, a two way ground return control circuit superimposed on both conductors of said trunk line in parallel, a first relay at each exchange connected to the negative terminal of the separate sources of current, a second relay at each exchange connected to the positive terminal of the separate sources of current, said first relays being normally connected also to said control circuit, means at each exchange for connecting said second relay to the control circuit in place of said first relay, and for re-connecting the first relay to said control circuit, thereby to operate and control said relays over said control circuit, and unidirectional current conducting devices in the circuit of each of said relays at both exchanges to prevent faulty operation of said relays due to differences of potential at the two exchanges during the times that both ends of said control circuit are connected to corresponding terminals of said separate sources of current.

4. In a telephone system, two exchanges, a trunk line connecting said exchanges, a two way impulse repeater at each end of said trunk line, a separate battery at each exchange, a grounded and an ungrounded terminal for each of said batteries, a two way ground return control circuit superimposed on both conductors of said trunk line in parallel, control relays at each repeater including a first relay at each repeater connected to the ungrounded terminal of said separate battery and a second relay at each repeater connected to the grounded terminal of said separate battery, said first relays being normally connected also to said control circuit, means at each repeater for connecting said second relay to the control circuit in place of said first relay, for interrupting this connection, and for re-connecting

said first relay, thereby to operate and control said control relays and said repeaters over said control circuit, and unidirectional current conducting devices in the circuit of said ungrounded battery terminals to prevent false operation of said control relays over said control circuit due to differences of potential at the two exchanges during the times that each end of said control circuit is connected to the ungrounded terminal of the separate battery at each exchange.

5. In a telephone system, two exchanges, a trunk line connecting said exchanges, a two way impulse repeater at each end of said trunk line, a battery at each exchange, grounded and ungrounded terminals for said batteries, a two way ground return control circuit superimposed on both conductors of said trunk line in parallel, control relays at each repeater including a first relay connected to the ungrounded terminal of the battery and a second relay connected to the grounded terminal of the battery, said first relays being normally connected also to the respective ends of said control circuit, means at each repeater for connecting said second relay to the control circuit in place of said first relay, for interrupting said last stated connection and for re-connecting said first relay to the control circuit in place of said second relay, thereby to operate and control said control relays and said repeaters over said control circuit, and unidirectional current conducting devices in the circuit of both grounded and ungrounded terminals of said batteries to prevent the mis-functioning of said control relays due to differences of potential at the ends of said control circuit during the times when both ends of said control circuit are connected to corresponding terminals of the battery at each exchange.

6. In a telephone system, two exchanges, simplex trunk lines connecting said exchanges, separate sources of line current at each exchange, two way ground return control circuits superimposed on said trunk lines, a plurality of control relays associated with each end of each said control circuit, said control circuits and said relays being connected to said sources of line current and controlled over both sides of the associated trunk line by reversals of line polarity and circuit interruptions at either end of the control circuit, and unidirectional current conducting devices associated with said control circuits to prevent line current flow over any of said circuits and resultant faulty operation of said circuit when both ends of said circuit are connected to equivalent polarities at the respective sources of line current.

7. In a telephone system, two exchanges, simplex trunk lines connecting said exchanges, separate sources of line current at each exchange, two way ground return control circuits superimposed on said trunk lines, said control circuits being connected to said sources of line current and operable over both sides of the associated trunk line in parallel, two way impulse repeaters at the ends of each of said trunk lines, a plurality of series relays associated with each of said repeaters and with the ends of said control circuits, said relays being operable by reversals of line polarity and circuit interruptions at either end of the control circuit, means at each repeater for effecting said reversals and said interruptions and controlling said relays and said repeaters in the process of making and releasing calls, and unidirectional current conducting devices associated with said control cir-

cuits to prevent line current flow over any of said circuits and resultant faulty operation of such circuit, while both ends of such circuit are connected to corresponding line polarities at each exchange.

8. In a telephone system, two exchanges, a trunk line connecting said exchanges, a separate source of current at each exchange, positive and negative terminals for each of said sources of current, a two way ground return control circuit superimposed on one conductor of said trunk line, a relay at each exchange, a winding on each said relay connected in series with said control circuit and normally connected to the positive terminal of the separate source of current at each exchange, means at each exchange for connecting the negative terminal of said source to said relay in place of said positive terminal, and for re-connecting the positive terminal, thereby to operate and control said relays over said control circuit and unidirectional current conducting devices in the circuit of said normally connected terminals at each exchange to prevent current flow over the control circuit and resultant false operation of said relays due to differences of potential at the two exchanges during the times that both ends of said control circuit are connected to the positive terminals of said separate sources of current.

9. In a telephone system, two exchanges, a trunk line connecting said exchanges, a separate source of current at each exchange, positive and negative terminals for each of said sources, a two way ground return control circuit superimposed on one conductor of said trunk line, a relay at each exchange, a winding on each of said relays connected in series with said control circuit and normally connected to the positive terminal of the separate source of current at each exchange, means at each exchange for connecting the negative terminal of said source to said relay in place of said positive terminal, and for re-connecting the positive terminal, thereby to operate and control said relays over said control circuit, and unidirectional current conducting devices in the circuit of each of said terminals at both exchanges to prevent faulty operation of said relays due to differences of potential at the two exchanges during the times that both ends of said control circuit are connected to corresponding terminals of said separate sources of current.

10. In a telephone system, two exchanges, a trunk line connecting said exchanges, a separate source of current at each exchange, line terminals for each of said sources of current, a two way ground return control circuit superimposed on one conductor of said trunk line, a control relay and associated equipment at each exchange, a winding on each said control relay each said winding being connected on one side to said control circuit and on the other side being normally connected to line terminals of like polarity at each exchange, means at each exchange for connecting the other line terminal to said winding in place of said normally connected terminal, and for re-connecting the normally connected terminal, said relays being operated and controlled over said circuit in response to said changes in terminal connections to operate said associated equipment, and unidirectional current conducting devices in the circuit of said normally connected line terminals to prevent false operation of said relays over said control circuit due to differences of potential at the two

exchanges while both relays are connected to the normally connected line terminals of the separate sources of current.

11. In a telephone system, two exchanges, a trunk line connecting said exchanges, a separate source of current at each exchange, line terminals for each of said sources of current, a two way ground return control circuit superimposed on one conductor of said trunk line, a control relay and associated equipment at each exchange, a winding on each said control relay, each said winding being connected on one side to said control circuit, and being normally connected on the other side to line terminals of like polarity at each end of said control circuit, means at each exchange for connecting the other line terminal to said winding and for re-connecting the normally connected terminal, said relays being controlled over said circuit in response to said changes in terminal connections to operate said associated equipment, and unidirectional current conducting devices in the circuit of each of said terminals at both exchanges to prevent mis-functioning of said relays due to differences of potential at the two exchanges, while both ends of said control circuit are connected to like line terminals of either polarity.

12. In a telephone system, two exchanges, a trunk line connecting said exchanges, a separate source of current at each exchange, a grounded and an ungrounded terminal for each of said sources of current, a two way ground return control circuit superimposed on one conductor of said trunk line, a relay at each exchange, a first winding on each said relay connected on one side to said control circuit, an artificial balancing line and biasing circuit at each exchange, a second winding on said relay having one side connected to said artificial balancing line and biasing circuit at each exchange, the other side of said windings being normally connected to the grounded terminal of the separate source of current at each exchange, means at each exchange for connecting the ungrounded terminal of said source to both windings of said relay in place of said grounded terminal, and for re-connecting the grounded terminal, said relays being operated and controlled over said control circuit in response to said changes in terminal connections, and unidirectional current conducting devices in the circuit of said grounded terminals at each exchange to prevent current flow over the control circuit and resultant false operation of said relays due to differences of potential at the two exchanges during the times that both ends of the control circuit are connected to the grounded terminals of said separate sources of current.

13. In a telephone system, two exchanges, a separate source of current at each exchange, grounded and ungrounded terminals for each of said sources of current, a two way ground return control circuit superimposed on one conductor of said trunk line, a control relay at each exchange, a first winding on each said relay connected in series with said control circuit, an artificial balancing line and biasing circuit at each exchange, a second winding on each said relay having one side connected in series with said artificial balancing line and biasing circuit at each exchange, the other side of said windings being normally connected together and to the grounded terminal of the separate source of current at each exchange, means at each exchange for connecting the ungrounded terminal of said source to both windings of said relay in place of

said grounded terminal and for re-connecting the grounded terminal, said relays being operated and controlled over said control circuit in response to said changes in terminal connections, and unidirectional current conducting devices in the circuit of each of said terminals at both exchanges to prevent mis-functioning of said control relays during the times that both control relays are connected to corresponding terminals of said separate sources of current.

14. In a telephone system, two exchanges, composed trunk lines connecting said exchanges, separate sources of line current at each exchange, two way ground return control circuits superimposed on said trunk lines, said control circuits being connected to said sources of line current and operable over one side of the associated trunk line by reversals and interruptions of line polarity at either end of the control circuit, and unidirectional current conducting devices associated with said control circuits to prevent line current flow over any of said circuits and resultant faulty operation of said circuit when both ends of said circuit are connected to corresponding polarities of the respective sources of line current.

15. In a telephone system, two exchanges, composed trunk lines connecting said exchanges, separate sources of line current at each exchange, two way ground return control circuits superimposed on said trunk lines, said control circuits being connected to said sources of line current and operable over one side of the associated trunk line, series control relays and associated equipment associated with the ends of said control circuits and said trunk lines, said relays being operable over said control circuits by reversals and interruptions of line polarity at either end of the control circuit, means at each exchange for effecting said reversals and said interruptions to operate and control said relays and said associated equipment, and unidirectional current conducting devices associated with said control circuits to prevent line current flow over any of said circuits and resultant faulty operation of said relays when both ends of said circuit are connected to equivalent line polarities, at each exchange.

16. In a telephone system, a two way ground return control circuit, a separate source of current at each end of said circuit, each end of said circuit being normally connected to like polarities of the separate sources of current, a plurality of control relays associated with each end of said control circuit, said relays being controlled over said circuit by reversals and interruptions of polarity at either end of the control circuit, and unidirectional current conducting devices associated with said control circuit to prevent faulty operation of said relays due to differences of potential between the two ends of the circuit while both ends of said circuit are connected to the same respective sides or polarities of the separate sources of current.

17. In a telephone system, a two way ground return control circuit, a separate source of current at each end of said circuit, each end of said circuit being normally connected to equivalent polarities of the separate sources of current, a plurality of control relays and associated equipment associated with each end of said control circuit, said relays being operable over said circuit by reversals and removals of polarity at either end of the control circuit to control the operation of said associated equipment, means

at each end of said control circuit for effecting said reversals and removals of polarity to operate and control said relays and said associated equipment, and unidirectional current conducting devices associated with said control circuit to prevent mis-functioning of said control circuit due to differences of potential between the two ends of the circuit during the times that both ends of said circuit are connected to the same respective sides or polarities of the separate sources of current.

18. In a telephone system, two exchanges, a two-way impulse repeater at each exchange, a trunk line connected to said repeaters, waystations in said trunk line, means in each repeater for seizing the distant repeater and repeating dial impulses to the distant repeater over said trunk line, means in each repeater for calling a given waystation and at the same time busying the distant repeater, means at each waystation for seizing and dialing through either repeater and at the same time busying the other repeater, and means at each waystation for calling another waystation and at the same time busying both repeaters.

19. In a telephone system, two exchanges, a two way impulse repeater at each exchange, a trunk line connected to said repeaters, telephone waystations in said trunk line, a plurality of points of access to said repeaters in each exchange comprising a first point of access used on through calls to the distant exchange and a second point of access used on calls to waystations, means in each repeater controlled from the first point of access for seizing the distant repeater and repeating dial impulses to the distant repeater over said trunk line on through calls, and means in each repeater controlled from the second point of access for code ringing on the trunk to signal the waystations and at the same time preventing dial impulses from reaching the trunk on calls to a waystation.

20. In a telephone system, two exchanges, a two way impulse repeater at each exchange, a trunk line connected to said repeaters, telephone waystations in said trunk line, a plurality of points of access to said repeaters in each exchange comprising a first point of access reserved for through calls to the distant exchange and a second point of access reserved for calls to waystations, means in each repeater controlled from the first point of access for seizing the distant repeater and repeating dial impulses to the distant repeater over said trunk line on through calls, means in each repeater controlled from the second point of access for impressing code ringing signals on the trunk to signal the waystation, means at said waystations for grounding the trunk when answering, and means in said repeaters responsive to said grounding of the trunk by the waystation for automatically disconnecting said code ringing signals from the trunk.

21. In a telephone system, two automatic exchanges, a two way impulse repeater at each exchange, said repeaters being accessible over different paths on outgoing calls, said paths depending on the nature of the call and the number dialed, a trunk line interconnecting said repeaters, telephone waystations in said trunk line, means in said repeaters for repeating dial impulses over said trunk line to the distant repeater when seized over one path reserved for through calls, means in said repeaters for placing code ringing signals on the trunk to signal said way-

stations when seized over a second path reserved for calls to waystations, means including said ringing signals for busying the distant repeater on such a call, means at said waystations for grounding the trunk when answering, means in said calling repeater responsive to said grounding of the trunk for cutting off the ring at the calling repeater and keeping said repeater busy until the waystation disconnects, and means in said distant repeater also responsive to the grounding of the trunk by the waystation for keeping the distant repeater busy on such a call until the waystation has disconnected.

22. In a telephone system, two automatic exchanges, a two way impulse repeater at each exchange, a code selector switch responsive to dial impulses in each repeater, different paths of access for said repeaters for outgoing calls, the path selected on any given call depending on the nature of the call and the number dialed, a trunk line interconnecting said repeaters, telephone waystations in said trunk line, means in said repeaters for repeating dial impulses over said trunk line to the distant repeater when seized over one path reserved for through calls, means in said repeaters including said code selector switch for placing code ringing signals on the trunk to signal said waystations and at the same time preventing the repetition of dial pulses to the trunk when seized over a second path reserved for calls to waystations, means at said waystations for grounding the trunk when answering, means in said repeaters responsive to said grounding of the trunk for cutting off the ring at the calling repeater, means for busying both repeaters during the establishment of a call, means responsive to the grounding of the trunk by the waystation for keeping both repeaters busy until the waystation disconnects, and means at said waystations for automatically removing said ground from the trunk upon disconnecting, thereby to permit the release of said repeaters.

23. In a telephone system, two automatic exchanges, a two way impulse repeater at each exchange, different paths of access to said repeaters for outgoing calls, incoming equipment associated with said repeaters at each exchange, said incoming equipment being normally seized on an incoming call by ground on the trunk, a simplex trunk line connecting said repeaters, telephone waystations in said trunk line, means in said repeaters for repeating dial impulses over said trunk line to the distant repeater when seized over one path utilized for through calls, means in said repeaters for placing code ringing signals on the trunk to signal the waystations when seized over a second path utilized for calls to waystations, means responsive to the initiation of such call to a waystation for seizing and busying the distant repeater and the associated incoming equipment, means responsive to the ringing signals on the trunk for freeing the distant incoming equipment while maintaining the busy on the distant repeater, means at said waystations for grounding the trunk when answering, means in said repeaters responsive to said grounding of the trunk for keeping both repeaters busy until the waystation disconnects, and means at said waystations for automatically removing the ground from the trunk when disconnecting, thereby to permit the release of said repeaters.

24. In a telephone system, two automatic exchanges, an impulse repeater at each of said exchanges, a simplex trunk connecting said repeaters,

ers, telephone waystations in said trunk, means at said waystations for making calls to either exchange by impulsing into either repeater with ground dial pulses over both conductors of the trunk in parallel, means in said repeaters responsive to said impulses for completing the call, means at said waystations for opening the trunk in the direction of the other repeater before dialing, means at said waystations for maintaining ground on the trunk in both directions and over both conductors of the trunk in parallel during such a call, means in said repeaters responsive to said ground for maintaining both repeaters busy to other calls until the waystation has disconnected, and said waystation ground maintaining means removing said ground and restoring the trunk to normal on disconnect, to permit the release of said repeaters.

25. In a telephone system two exchanges, a two-way impulse repeater at each of said exchanges, a trunk line connecting said repeaters, magneto telephone waystations in said trunk line, means at said waystations comprising a hand generator for calling another waystation by code ringing on the trunk, means at said waystations for grounding the trunk in both directions from both waystations after the called waystation has answered, means in said repeaters responsive to the code ringing on the trunk for busying both repeaters, means in said repeaters responsive to the ground on the trunk for holding both repeaters busy until both waystations have disconnected, and said waystation grounding means removing said ground from the trunk on disconnect to release said repeaters.

26. In a telephone system, two automatic exchanges, a two-way impulse repeater at each exchange, incoming equipment associated with said repeaters at each exchange, a trunk line connecting said repeaters, magneto telephone waystations in said trunk line, means at said waystations comprising a hand generator for calling another waystation by code ringing on the trunk, means at said waystations for grounding the trunk in both directions from both waystations after the called waystation has answered, means in said repeaters responsive to the code ringing on the trunk for busying both repeaters and at the same time preventing seizure of the associated incoming equipment, means in said repeaters responsive to the subsequent grounding of the trunk by the waystations to maintain this busy on both repeaters until both waystations have disconnected, and said waystation grounding means removing said ground from the trunk on disconnecting, to release said repeaters.

27. In a telephone system, two automatic exchanges, a separate battery at each exchange, a two way impulse repeater at each exchange, a trunk line connecting said repeaters, a two way ground return control circuit superimposed on both conductors of said trunk line, the ends of said control circuit being normally connected to negative polarity at the separate batteries, magneto telephone waystations in said trunk line, incoming equipment associated with each repeater in each exchange, a code selector switch responsive to dial impulses in each repeater, different paths for seizing said repeaters for outgoing calls depending on the nature of the call and the number dialed, means in said repeaters for repeating dial impulses to the distant repeater over said control circuit and completing the call in response to seizure over one path reserved for through calls, means in said repe-

peaters including said code selector switch for placing code ringing signals on the trunk to signal said waystations and at the same time preventing the repetition of dial impulses to the trunk in response to seizure over a second path reserved for calls to a waystation; means responsive to the initiation of a repeater to waystation call for seizing and busying the distant repeater and the associated incoming equipment, code ringing signal responsive means in said distant repeater operated by said ringing signals to free the distant incoming equipment while maintaining the busy on said distant repeater, means at said waystations for placing waystation ground on the trunk when answering and for removing said ground from the trunk upon disconnecting at the termination of the call, means in the calling repeater responsive to said waystation ground for stopping the code ringing signals, busying means in said repeaters responsive to said waystation ground for maintaining the busy on both repeaters until the waystation has disconnected, and for permitting the release of said repeaters after the waystation has disconnected and removed waystation ground from the trunk; dialing means at said waystations for making calls to either exchange by impulsing into the selected repeater with waystation ground pulses over said trunk and said control circuit, means in said selected repeater responsive to said impulses to complete the call, trunk splitting keys at said waystations for opening the trunk in the direction of the other repeater before dialing and at the same time connecting waystation ground to this end of the trunk to keep said other repeater busy for the duration of the call, waystation ground being also maintained on the trunk in the direction of the called repeater through said dialing means to hold said called repeater after the cessation of dialing, means in said waystations responsive to disconnection by the waystation at the termination of the call for automatically removing waystation ground from both ends of the trunk and restoring the continuity of said trunk, thereby to permit the release of said repeaters and their restoration to normal operating condition; a hand generator at said waystations for calling another way station by code ringing on the trunk, the previously stated code ringing signal responsive means in both repeaters being operated by said code ringing on the trunk to busy both repeaters and prevent seizure of the associated incoming equipment in either exchange, said busy condition being maintained after the ringing period by waystation ground from both calling and answering waystations until both waystations have disconnected; and means comprising a unidirectional current conducting device in the ground return control circuit at each exchange to prevent false operation of said control circuit and said repeaters due to differences of battery potential at the two exchanges while the system is at rest.

28. In a telephone system, a first exchange, a second exchange, a trunk line connecting said exchanges, a repeater in each exchange terminating said trunk line, subscriber waystations on said trunk line between said exchanges, a pair of trunk splitting keys at each waystation controlling the continuity of said trunk line between said exchanges, means responsive to the operation of the first of said trunk keys at any waystation in initiating a call over said trunk line to said first exchange for splitting said

trunk line into two sections with the calling waystation connected to only the first of said sections connected to the first exchange and for grounding the second of said sections connected to the second exchange, repeater busying means in the repeater at the second exchange responsive to the grounding of said second section for busying said repeater, waystation calling means for operating the repeater at the first exchange over said first section to extend the call, means responsive in case the second of said trunk keys at any waystation is operated in initiating a call over said trunk line to the second exchange for splitting said trunk line into two sections with the calling waystation connected to only the second of said sections connected to the second exchange and for grounding the first of said sections connected to the first exchange, repeater

busying means in the repeater at the first exchange responsive to the grounding of said first section for busying said repeater, said waystation calling means operating the repeater at the second exchange to extend the call, a hand generator at each waystation for calling other waystations on said trunk line by code ringing on said trunk line, ringing responsive means in each repeater operated in response to receipt of ringing signals for operating both said repeater busying means to busy both repeaters during the ringing period, means at each waystation for grounding said trunk line in both directions therefrom, and both said repeater busying means being responsive to the grounding of said trunk line by said last means for maintaining both repeaters busy after the ringing period.
